UNITED STATES PATENT OFFICE.

NICOLAUS KOLBY, OF CHICAGO, ILLINOIS.

PHONOGRAPH-RECORD HOLDER.

1,371,629.

Specification of Letters Patent.

Patented Mar. 15, 1921.

Application filed March 29, 1920. Serial No. 369,799.

To all whom it may concern:

Be it known that I, NICOLAUS KOLBY, a citizen of the United States, residing at Chicago, in the county of Cook and State of Illinois, have invented certain new and useful Improvements in Phonograph-Record Holders, of which the following is a specification.

This invention relates to holders or racks for containing disk phonograph records and has for its main object to provide a simple, inexpensive and efficient holder or rack which may be located within the usual record filing space of a phonograph cabinet, if desired, or may be located at any convenient place outside of said cabinet, and will serve to support the records in compact order and in such a manner that individual records may be quickly withdrawn from or returned to the holder without danger of injury through contact with each other or with the metallic parts of the holder.

Another object is to provide a holder wherein the records shall be supported side by side in close parallel relation and without danger of striking each other.

Another object is to provide an improved back-stop for the records that shall be foldable within the main frame of the holder for economy of space in packing and shipping the device.

A still further object is to provide an improved holder capable of receiving and containing disk records of different sizes.

Other objects and advantages of the invention will be apparent to those skilled in the art from the following detailed description, taken in connection with the accompanying drawing, in which—

Figure 1 is a front elevation of my improved holder; and,

Fig. 2 is a vertical transverse section of the same, the back-stop being shown in full lines in its operative position, and in dotted lines in its folded or idle position.

Referring to the drawing, 5 designates the top member, 6 the bottom member, and 7 the vertical side members of a rectangular wooden frame. Extending between the top and bottom frame members 5 and 6 is a series of parallel round metal rods 8, the central portions of which are bent or bowed rearwardly as shown at 8'. The upper and lower ends of these rods lie against the front faces of the frame members 5 and 6, and are entered within grooves or mortises 9 and 10 formed in the rear faces of upper and lower fastening strips 11 and 12 secured to the front faces of the frame members 5 and 6, respectively as by means of screws 13. To prevent turning movement of the rods, one end of each rod (lower end as herein shown) is formed with a forwardly extending foot 14 which lies within a hole or socket 15 formed in the attaching strip to receive it. 65

On each rod is mounted a series of spacing sleeves 16 of rubber, felt or like soft material, these sleeves serving to space and laterally support the record disks lying between adjacent rods and to prevent contact of the disks with the metal rods which might scratch and otherwise injure the grooved surfaces of the disks. It will be observed that the rearward bending of the intermediate portions of the rods, with the application of spacing sleeves 16 at the upper, lower and intermediate points of the bent portions 8' insures three points of contact on the disk which are out of line with each other, thereby preventing any lateral tilting 75 or swinging of the disks which might cause them to strike each other, and holding the disks to true parallelism.

Hinged at 17 in the vertical side frame members 7 are the ends of a bail-shaped 85 back-stop 18 that serves to limit the extent to which the record disks can be entered in the holder. I have herein shown the transverse member of this back-stop, with which the edges of the disks come in contact, as 90 comprising two relatively offset portions 19 and 20, the portion 19 of shorter radius being adapted to coöperate with the small records indicated at A by dotted lines in Fig. 2, and the portion 20 of longer radius 95 being adapted to coöperate with disks of larger size indicated by dotted lines at B. This back-stop is capable of being swung upwardly to a position within the main frame, as indicated by dotted lines in Fig. 2, 100 thus enabling the holder to be packed within a box of substantially the dimensions of the frame itself. When swung downwardly to operative position, the sides of the back-stop are arrested and supported in proper 105 position by pins or screws 21 in the inner sides of the frame members 7, as clearly shown in Fig. 2.

By reference to Fig. 2, it will be noted that the top surface of the lower frame bar 110 6 is inclined downwardly and rearwardly, as shown at 22, thus causing the record disks,

when entered between the supporting rods to roll by gravity rearwardly into contact with the back-stop. This inclined surface 22 is preferably provided with a cloth or felt covering 23 to avoid wear on the peripheries of the disks.

On the front of the bottom fastening strip 12 is secured an index strip 24 containing numerals identifying the records in the 10 holder.

It is believed that structure, manner of use, and advantages of the invention will be readily apparent to those familiar with devices of this character without further detailed description. Manifestly, the structural details may be modified without departing from the principle of the invention or sacrificing any of the advantages thereof. Hence, I reserve all such variations and 20 modifications as fall within the spirit and purview of the appended claims.

I claim:—

1. A phonograph record holder, comprising a rectangular frame, a series of parallel 25 rods mounted in and extending between opposite sides of said frame, and a back-stop extending rearwardly of and hinged to said frame and foldable to an idle position within the latter.
2. A phonograph record holder, comprising a rectangular upright frame, a series of parallel rods mounted in and extending

between the upper and lower sides of said frame, and a bail-shaped back-stop hinged in the vertical side members of said frame 35 and foldable between an operative position extending rearwardly of said frame and an idle position within said frame.

3. A phonograph record holder, comprising a rectangular upright frame, a series of 40 parallel rods mounted in and extending between the top and bottom members of said frame, and a bail-shaped back-stop mounted on and extending rearwardly of said frame, the transverse member of said back-stop 45 having relatively offset portions lying at different distances from said frame and adapted to coöperate with record disks of different diameters.

4. A phonograph record holder, comprising a rectangular upright frame, a series of parallel rods mounted in and extending between the top and bottom members of said frame, and a bail-shaped back-stop hinged in the vertical side members of said frame 55 and foldable between an operative position extending rearwardly of said frame and an idle position within said frame, the transverse member of said back-stop having relatively offset portions lying at different radial distances from the axis of said back-stop and adapted to coöperate with records of different diameters.

NICOLAUS KOLBY.
